CLAIM

The ornamental design for a "razor holder", as shown and described.

DESCRIPTION

FIG. 1 is a perspective view of a "razor holder" showing our new design;

FIG. 2 is a right side elevational view shown in combination with a razor for illustrative purposes;

FIG. 3 is a right side elevational view;

FIG. 4 is a front end elevational view thereof;

FIG. 5 is a rear end elevational view thereof;

FIG. 6 is a sectional view thereof taken along the line 6—6 of FIG. 3;

FIG. 7 is a sectional view thereof taken along the line 7—7 of FIG. 3;

FIG. 8 is a sectional view thereof taken along the line 8—8 of FIG. 3;

FIG. 9 is a top plan view thereof;

FIG. 10 is a bottom plan view thereof;

FIG. 11 is a side elevational view shown in a partially folded position; and,

FIG. 12 is a side elevational view shown in a fully folded position.

The broken line showing of the razor is for illustrative purposes only and forms no part of the claimed design.
